Fig - 5Fig - 6Fig - 7

FIG. 1 is a front and left side perspective view illustrating a radio cabinet showing my new design;

FIG. 2 is a front elevational view;

FIG. 3 is a right side elevational view;

FIG. 4 is a bottom plan view taken from line 4—4 of FIG. 3;

FIG. 5 is a top plan view thereof;

FIG. 6 is a left side elevational view; and

FIG. 7 is a rear elevational view.

The characteristic features of my design are the appearance of a rectangle with rounded corners of the cabinet in top plan view and the protruding control knobs on the cabinet sides.

I claim:

The ornamental design for a radio cabinet, as shown and described.
